UNITED STATES PATENT OFFICE

2,508,147

DOUBLE-ACTING SLIDE FASTENER

Emery Dutch, New York, N. Y.

Application October 8, 1945, Serial No. 620,911

6 Claims. (Cl. 63—5)

1

This invention relates to the so-called slide fastener devices, and has for its main object to provide a device of this type, which, so to say, will be "double acting."

In slide fastener devices now used or heretofore proposed, a closing and opening member slides along and between two rows of locking elements, and through its movement in one direction closes and in the other direction opens the device. In my present invention said member moving in either direction will continually open the slide fastener in front of it and close the same at its rear.

Another aim of this invention is to provide a double acting slide fastener, as has been characterized hereinbefore, in which a member will be adapted to slide along a separation line in a flexible object, like a bracelet, belt, etc., and will stay locked and secured in any position thereof during its travel, securely closing the separation line, both, in front, and in the rear of it.

Still another object of my invention is to apply my novel double acting or "floating" slide fastener to appropriate articles, like a bracelet, belt, etc., where an adjusting of the active portion of such an article is desired, and where it is desired to secure the same in such adjusted position.

Another important object of my invention is to provide an element which may slidably move along a separation line in a flexible article, like a bracelet, chain, belt, piece of fabric, etc., and which element will automatically be secured in any of its positions so that an appropriate member may be secured thereto at any desired location in that separation line.

Other objects of my invention will be partly pointed out and partly apparent as the specification of the same proceeds.

In the drawings forming a part of this specification, and accompanying the same:

Fig. 1 is a fragmentary, semi-diagrammatic plan view of a slide fastener constructed according to my invention, portions of the same being broken away, and other portions being shown in section;

Fig. 2 is a side elevational view of the same, other portions being shown broken away;

Fig. 3 is a perspective view of a bracelet watch to the chain of which my invention has been applied.

Fig. 4 is a transverse sectional view of the overlapping portions of the bracelet chain at one end thereof, as indicated by the line 4—4 in Fig. 3, and being on a much larger scale than Figs. 1 to 3.

2

Fig. 5 is a longitudinal sectional view of the overlapping portions at the other end of the chain as indicated by line 5—5 in Fig. 3, this figure being on the same scale as Fig. 4.

Fig. 6 is an elevational view of the hinge indicated in Fig. 4.

Referring now to the drawings more in detail by characters of reference, the numeral 10 indicates my novel double acting slide fastener, in general, the embodiment shown using one of the well known types of the so called "zipper" slide fasteners. Said fastener, as will be understood by those versed in the art, is composed of two oppositely placed rows 11 and 12 of interlocked elements which are releasable from one another, or may be put into a closed locking position, as desired.

A slideable sleeve like member 13 is arranged around a portion of the two rows of oppositely placed locking elements 11 and 12, said sleeve being wider in the center, as at 14, and being narrower at both ends, as at 15 and 16. A central hollow pin portion 17 is integral with the top and the bottom of the slideable sleeve 13. The sleeve 13 and the central hollow pin 17, operate similarly to the closing sleeve and the opening or releasing pin, respectively, in any of the usual well known "zipper" slide fasteners, but in my invention, both the sleeve 13 and the central separating pin 17 are double acting, that is, they open the two rows of locking elements 11 and 12 in front of them and close said two rows to the rear of them when they move in either direction, to the right as indicated by arrow 18, or the left as indicated by arrow 19. This effect is brought about by making the closure sleeve 13 longer than is the case with the present zipper fasteners, and making both its ends constricted, as shown at 15 and 16, whereby moving the sleeve 13 along the rows 11 and 12 of locking elements, the rear end thereof will always close the elements 11 and 12 which were opened by the center pin 17, and said center pin will provide for such opening in both directions.

In a word, the pin 17 will open the respective locking elements 11 and 12 only around its circumference and as far as the bulging out portion of the sleeve 13 will permit it, and all the rest of the locking elements 11 and 12, both, in front and to the rear of the sliding sleeve 13, whether it will move to the right or to the left, will always be kept locked.

However, in addition to the normal locking action of the slide fastener element 11 and 12, I may employ extra locking means to secure the

sleeve 13 in the position to which it arrived. One such extra locking means is shown in Figs. 1 and 2.

Slidable pin 50 is arranged in the through-going elliptical vertical tube 17, said tube being formed in the center of the sliding sleeve 13, secured at the top and bottom to the top and bottom plates of said sleeve, or possibly being integral therewith. Within the sleeve 13 and between the two rows of locking elements 11 and 12, said pin 50 carries a disk 51, while its top may project over the upper surface 52 of the sleeve and may have an operating button 53 secured thereon.

Normally pin 50 is in its neutral initial position, in the wide center of the tube 17 (and sleeve 13) as indicated by dotted lines in Fig. 1.

Disk 51 slides in slots 54 in the longitudinal sides of the tube 17 and projects therethrough at the center to a small distance only, in each side. In such a center position of the pin 50, the disk 51 will not reach the two rows of elements 11 and 12 widely separated at that place.

When, however, the slide 13 has been moved to a desired position, pin 50 will be moved to one end of the tube 17, as shown by the full line position thereof in Figs. 1 and 2, it being shown at the left hand end of the tube. At such an end position of the pin 50, the two sides of the disk 51 will press the elements 11 and 12, at that place, against the vertical side walls 55 and 56 of the sleeve 13, and this way lock said sleeve by frictional brake action.

In Fig. 3, I show one application of my novel double acting locked slide fastener.

The figure shows a wrist watch 30, with its bracelet chain, generally indicated by the numeral 31. Said chain, in the embodiment shown will be made of two slide fasteners 32 and 33 of my invention, each being secured at one of its ends to the wrist watch, as indicated at 34 and 35, while their other ends 36 and 37 will be free.

Opening and closing slidable sleeve members 38 and 39 are inserted into the respective halves 32 and 33 of the bracelet 31, moving therein and being constructed similarly as has been explained hereinbefore in connection with Figs. 1 and 2.

The end 36 of the half 32 of the bracelet 31 is secured to the sliding sleeve member 39 in the other half 33 thereof, and this arrangement will serve for adjusting the bracelet as desired by the wearer.

It will be seen that when the sleeve 39 is moved in its slide fastener 33 outwardly, as indicated by the arrow 40, the bracelet 31 will be made wider, while upon a reverse moving thereof (arrow 41), the bracelet will be tightened. Sleeve 39 will be locked in any of its positions in fastener 33, and the bracelet this way will be secured in its adjusted position.

In Fig. 4 I show one embodiment of securing the chain end 36 to the underside of the sliding member 39, and in this embodiment, a sleeve 60 will be secured on said underside, and a pin 61 will be passed therethrough, the two ends of the pin being pivotally engaged by the sleeves 62 at the two sides of the chain end 36.

To further secure the adjusted position of the bracelet and, mainly, to take up the loose end 37, the second sliding sleeve 38, with its associated parts, is arranged in the slide fastener 32. This sliding sleeve 38 may have an appropriate recess into which may be secured the free end 37 of the other fastener chain 33, as by a hook 43. In the embodiment in Fig. 5, the elliptical tube

17 is used for said recess, the upper plate of the sliding member 38 being extended thereover, as indicated at 52a. The securing pin 50 will be omitted in member 38.

5 After the bracelet has been adjusted by the sliding of sleeve member 39, in chain 33, the other sleeve member 38 in chain 32 will be moved as necessary to secure the free end 37 of chain 33 thereinto, as will be understood, and in this 10 manner to keep the inactive portion 37a of fastener 33 secured and taut.

I have shown my invention as applied to a bracelet, but, obviously its constructions and principles are applicable to any similar device, 15 like belts or bands, and in a way, the two parts of a bracelet and the watch in between, jointly, is a band.

While I have shown a preferred embodiment of my invention, it is to be understood that changes 20 and variations may be resorted to in the elements, construction and combination of my invention, and I reserve my rights to such changes and variations as are within the spirit of this specification, and the scope of the claims hereunto appended.

What I claim as new and want to protect by Letters Patent of the United States is:

1. In an elongated adjustable article having 30 flexible end portions, a separation line in one, the first, of said portions, oppositely placed co-operating interlocked elements along the two sides of said separation line, a member adapted to move in said separation line in either direction and to open said locked elements in front 35 of it and close them at its rear, whereby it will be secured in any of its positions by the elements locked in said line at both sides in the front and to the rear thereof, and means to secure the other, the second, flexible end portion to said movable member whereby the size of said article may be adjusted and the same secured in such adjusted position.

2. In a device, as set forth in claim 1, each of 45 said sliding members including a part embracing said locking elements and being slidable along the same, both end portions of it being narrowed to force said elements to each other and into locked position, and the center portion of said part being wider to allow outward movements of 50 said elements when separated, the respective portion of the securing means for the end of said first flexible portion being carried on the exposed outer surface of said second sliding member.

3. In an elongated adjustable article having 55 flexible end portions, a separation line in one, the first, of said portions, oppositely placed co-operating interlocked elements along the two sides of said separation line, a member adapted to move in said separation line in either direction

60 and to open said locked elements in front of it and close them at its rear, whereby it will be secured in any of its positions by the elements locked in said line at both sides in the front and to the rear thereof, and means to secure the other, the second, flexible end portion to said sliding member whereby the size of said article may be adjusted and the same secured in such adjusted position, a similar line of separation in said second flexible portion, having slide fas-

70 tener locking elements and a second sliding member therein, similarly acting as those in said first separation line, and cooperating means in said second sliding member and the end of said first flexible portion whereby after adjusting the article by said first sliding member, said second

sliding member may be appropriately moved in said second separation line carrying the end of said first flexible portion secured thereto to keep the overlapping portions of said first and second band portions fastened to and taut on one another.

4. In an elongated adjustable article having flexible end portions, a separation line in one, the first, of said portions, oppositely placed cooperating interlocked elements along the two sides of said separation line, a member adapted to move in said separation line in either direction and to open said locked elements in front of it and close them at its rear, whereby it will be secured in any of its positions by the elements locked in said line at both sides in the front and to the rear thereof, and means to secure the other, the second, flexible end portion to said sliding member whereby the size of said article may be adjusted and the same secured in such adjusted position, said movable member having a part embracing said locking elements and being slideable along the same, both end portions of it being narrowed to force said elements to each other and into locked position, and the centre portion of the same being wider to allow outward movements of said elements when separated, said movable member carrying separating means being in the form of an elliptical tube, a pin movable in said tube in the direction of said separation line, a disk on said pin slideable in slots in the sides of said elliptical tube, wherein in a center position of the pin, said disk will be inactive, but in any end position thereof the disk will press said locking elements against the side walls of said part and thereby cause locking frictional action therebetween.

5. In an elongated adjustable article having flexible end portions, a separation line in one, the first, of said portions, a member adapted to move in said separation line in either direction, means along said separation line adapted to temporarily lock said member in any of its positions, and a means to secure the other, the second flexible end

portion of said article to said movable member, whereby a moving of said member will carry said second end portion along said first end portion inwardly or outwardly and thereby adjust the size of a loop formed by said article.

6. In an elongated adjustable article having flexible end portions, a separation line in one, the first, of said portions, a member adapted to move in said separation line in either direction, means along said separation line adapted to temporarily lock said member in any of its positions, and a means to secure the other, the second flexible end portion of said article to said movable member, whereby a moving of said member will carry said second end portion along said first end portion inwardly or outwardly and thereby adjust the size of a loop formed by said article, a second separation line in said second end portion, a second member movable in said second separation line in either direction, means along said second separation adapted to temporarily lock said second member in any of its positions, said first flexible end portion of the article being secured to said second movable member whereby upon adjusting the size of the loop formed by the article through said first member, the device may be additionally locked and the overhanging part of said first flexible end thereof secured in a smooth condition by appropriately moving said second member in its separation line.
